UNITED STATES PATENT OFFICE

HUGH WALLACE AND FRANCIS E. STEVENSON, OF DAYTON, OHIO, ASSIGNEES, BY
MESNE ASSIGNMENTS, TO FRIGIDAIRE CORPORATION, A CORPORATION OF DELA-
WARE

MOUNTING FOR A DRIVING AND A DRIVEN DEVICE

Application filed November 3, 1926. Serial No. 145,933.

This invention relates to improvements in apparatus for mounting work devices which are operatively connected, and particularly to such devices as are used in connection with 5 refrigerating machines.

It is among the objects of the present invention to provide a mounting device of simple structure and design for operatively connected driving and driven members. Another object is to provide for the adjustment of either of said members relative to the other for purposes of maintaining efficient operating connections.

Further objects and advantages of the 15 present invention will be apparent from the following description, reference being had to the accompanying drawings wherein a preferred embodiment of one form of the present invention is clearly shown.

20 In the drawings:

Fig. 1 is a side elevation of the refrigerating machine, a cover portion being removed to show the compressor element.

Fig. 2 is a view taken in a direction of the 25 arrow 2 of Fig. 1;

Fig. 3 is a view taken in a direction of arrow 3 in Fig. 1;

Fig. 4 is a fragmentary sectional view taken along the line 4—4 of Fig. 2;

30 Fig. 5 is a fragmentary sectional view taken along the line 5—5 of Fig. 2; and

Fig. 6 is a detailed sectional view taken along the line 6—6 of Fig. 4.

In the mounting of work devices comprising a driving element and a driven element it is desirable to make provision for adjusting the relative positions of these elements. This is frequently the case in compressors driven by motors and particularly those used 35 in iceless refrigerators. Such means for adjustment should be readily accessible without necessitating dismounting of the apparatus. These features are provided by the arrangement herein described.

40 Referring to the drawings, the numeral 20 designates the cabinet of the refrigerating machine having a compartment 21 including the operating mechanism of the refrigerator. This mechanism comprises the driving member

or compressor 23 and the condenser 24. The motor 22 and the compressor 23 are provided with pulleys 25 and 26 respectively, operatively connected by means of the belt 27. Conduit 28 provides communication between 55 the compressor 23 and the condenser 24.

In the chamber 21 of the refrigerator there is provided a mounting platform comprising parallel side members 30 and 31. Each of these side members are of angular construction having right angled arms 32—33 and 34—35 respectively. The respective arms 32 and 34 of the side members 30 and 31 lie in the same horizontal plane and extend toward the axis of the mounting frame. Side member 30 is provided with a longitudinal channel 36 formed between the arm 32 and a strip 37, which strip is held in spaced relation with the arm 32 by means of a plurality of spacer blocks 38, interposed between said arm and strip. Screws 39 secure the spacer blocks 38 and the strip 37 to the arm 32. 60

The mounting platform 40 supports the driving element 22. Any number of suitably spaced apertures may be provided in this mounting platform so that various motors, having different spaced apertures for receiving mounting studs 41, may be secured to this platform. Outwardly extending flanges 42 and 43 are provided on opposite sides of the 65 platform 40, the flange 42 being adapted to be supported slidably in the channel 36. The flange 43 rests upon clamping members, comprising head portions 48 and screw threaded stud portions 49, the latter extending 70 through apertures formed in the arm 34 and having nuts 50 thereon. As shown in Fig. 4 the flange 43 resting upon the head portions 48 of the clamping members, is adapted tightly to be clamped between the head portions 75 and the arm 34 of the member 31 when the nuts 50 are screwed against said arm. On the other hand when the nuts 50 are operated in the opposite direction, the heads 48 will be moved away from the arm 34, thus releasing 80 the clamping members and thereby permitting the platform 40 to be slid in the channel 36 and the channel formed between the heads 48 and the arm 34.

85 Platform 40 has an ear 51 formed thereon 100

59 member or electric motor 22, the driven member

in such a location that the screw threaded aperture 52 in said ear lies intermediate the members 30 and 31 of the frame.

Cross bars 55 and 56 are supported by the side members 30 and 31 in spaced relation, screw studs 57 holding the cross bars rigidly in position. The compressor 23 is rigidly mounted on these cross bars, being securely held thereon by studs 58. Cross bar 55 has a downwardly extending apron 59 provided with a curved slot 60, the closed end of which lies in axial alignment with the screw threaded aperture 52 in the ear 51.

The means secured to either one of the driving or driven members and engaging the other of said members for adjusting the relative position of said members on the frame, comprise a screw having a shank portion 60 screw threadedly engaging the aperture 52 of the ear 51. A yoke shaped head is provided on the screw, said yoke shaped head comprising an intermediate portion 63 having flange portions 61 and 62. Intermediate portion 63 is of such diameter that it may be inserted in the slot 60, the flange portions 61 and 62 engaging with opposite sides of the apron 59 when the screw is so inserted in the slot. In order to facilitate the operation of the screw, flanges 61 and 62 are hexagonal shape 30 to receive a suitable tool.

As has been mentioned heretofore, this device is provided for purposes of maintaining efficient connections between the motor 22 and the compressor 23. Should the belt 27 be 35 too loose, the motor 22 would not drive the compressor 23 properly. In such a case the nuts 50 on the clamping members should be released and then the screw, interposed between the compressor and the motor, 40 should be operated so that the screw threaded connection with the motor platform will move the said platform away from the compressor. When the belt has been properly tensioned, the nuts 50 should again be tightened, thereby rigidly clamping the motor supporting platform 40 in position on the frame. Should the belt 27 be too tight, the platform 45 may be released and the screw operated in the opposite direction.

It is apparent that since the clamping or locking means 50 and its related parts are located on one side of the frame, preferably the "front" side or the one accessible when the door of the refrigerator compartment is 55 removed or opened, adjustment of the apparatus may be effected very conveniently and without requiring the operator to reach in behind the body of the motor, intervening piping or the like.

While the form of embodiment of the present invention as herein disclosed, constitutes a preferred form, it is to be understood that other forms might be adopted, all coming within the scope of the claims which follow.

What is claimed is as follows:

1. In a device of the character described, the combination with a frame having parallel side members, one of which is provided with a longitudinal channel; a platform for supporting a work device, said platform having oppositely disposed flanges, one of which is slidably supported in the said channel; adjustable supporting means carried by the other side member of the frame providing a support for the other flange of the platform and being operable to clamp said flange securely to the frame; cross bars rigidly mounted on the frame for supporting a work device; and means interposed between one of the cross bars and the platform operable to move the said platform relative to the cross bars when the adjustable supporting means is released.

2. In a device of the character described, the combination with a frame having parallel side members, one of which is provided with a longitudinal channel; a platform for supporting a work device, said platform having flanges extending from the opposite sides thereof, one of which is adapted to be slidably supported in the said channel; a plurality of clamping members carried by the other side member of the frame, said clamping members comprising screw threaded shank portions extending through apertures in said side members and head portions upon which rests the other flange of the platform; nuts on said clamping member shanks, operable to clamp the platform flange securely against the side member of the frame; cross bars rigidly secured to the side members of the frame; and means interposed between one of said cross bars and the platform, operable to move the platform relative to the cross bars when said nuts are operated to release the platform flange.

3. In a device of the character described, the combination with a frame having parallel side members, one of which is provided with a longitudinal channel; a platform for supporting a work device, said platform having flanges extending from opposite sides thereof, one of which is slidably supported in the said channel; means for supporting the other flange of the platform, said means being operable to clamp the said flange tightly against its respective side member; an ear on the platform, provided with a screw-threaded aperture axial of the frame; cross bars rigidly supported between the two parallel sides of the frame and adapted to have a work device mounted thereon, one of said cross bars having a ledge parallel to the ear of the platform, provided with a curved slot; and an adjusting member including a yoked head insertable in said slot so as to be rotatably anchored therein, said member having a threaded shank portion extending into the aperture of the platform ear.

4. In a device of the character described the combination with a support having a slideway portion and carrying a driving device and a device driven thereby, one of said devices being slidable within said slideway and being guided therein by a flange on one side of said support, means for adjustably spacing said devices having one end thereof held stationary and the other end engaging said slidable device, and flange means cooperating with the other side of said support for locking said slidable member in adjusted position, said locking means comprising a member adapted to bear upon the flange of said locking means, and screw means for tightening said member against said flange, said screw means being exteriorly accessible.

In testimony whereof we hereto affix our signatures.

20 HUGH WALLACE.
FRANCIS E. STEVENSON.
